CLAIM

The ornamental design for a wearable health sensor, as shown and described.

DESCRIPTION

FIG. 1 is a front elevation view of a wearable health sensor, showing our new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a back elevation view thereof; and,

FIG. 7 is a front, top and right side perspective view thereof. The broken line portion of the figure drawings is included to show unclaimed subject matter only and forms no part of the claimed design.

1 Claim, 7 Drawing Sheets(56)
